United States Patent Office.

JOHN McFARLANE GRAY, OF LIVERPOOL, ENGLAND.

Letters Patent No. 98,371, dated December 28, 1839.

IMPROVEMENT IN STEAM STEERING-APPARATUS.

The Schedule referred to in these Letters Patent and making part of the same.

To all whom it may concern:

Be it known that I, JOHN McFARLANE GRAY, engineer for George Forrester & Co., at Vauxhall Foundry, Liverpool, in the county of Lancaster, in that part of her Britannic Majesty's dominions called England, have invented certain new and useful "Improvements in Steering-Apparatus, referring to a Steering-Telegraph and Rudder-Indicator and a Steam Steering-Engine;" and I do hereby declare that the following is a full and exact description thereof.

My invention consists of two parts: the first, part refers to a steering-telegraph and rudder-indicator, and the second part refers to a steam steering-engine.

I use the term "rudder-indicator," as its name implies, and the word "telegraph" as a name for that portion of the apparatus which is worked by the man at the bridge.

First, the telegraph and indicator. Heretofore such apparatus has been constructed with two sets of connections, one for telegraphing from the bridge to the stern, and the other for indicating the actual position of the rudder. Now, according to my invention, these are so constructed as to form but one machine.

Hitherto the telegraph has been worked at the bridge, generally by a small motion of a wheel, which is usually stationary while the rudder is being moved; but, according to my invention, the telegraph hand-wheel is moved to about the same extent and in the same manner as a common steering-wheel, and must be kept in motion while the rudder is being moved beyond a certain distance, so that any seaman, who can steer at the helm, can, without further instructions, also work the wheel at the bridge.

The principal object I have had in view in this part of my invention has been to contrive an efficient telegraph to answer all the requirements of steering by men, and at the same time to be applicable to steering by steam-power, without alteration in the working of the telegraph, and without the intervention of a man between the person at the telegraph-wheel and the steam steering-engine.

In constructing a steering-telegraph and rudder-indicator, according to my invention, I carry a line of small shafting, B B, in any convenient way, from a hand-wheel, A, called the telegraph hand-wheel, at the bridge, to a telegraph-dial, H F, aft, placed near the helm.

Aft, is a screwed shaft, which I will suppose to be a vertical shaft, D. It works in a nut, and is able to move a certain distance in the direction of its axis, by revolving in the nut.

This nut is attached to, or is cast in one piece with a wheel, D², and the nut and the wheel turn together in a bearing, and are provided with collars, to prevent longitudinal motion.

This wheel D² is connected, by gearing N², with a wheel, N¹, which revolves with the steering-wheel shaft N, so that the nut D² turns only when the steering-wheel shaft N, and consequently the rudder, not represented, is turned.

The screwed shaft D carries a piece, D⁴, containing a turned groove, and a sliding block, Q², lies in this groove.

A pin in this block is attached to a lever, Q¹, which I will designate as the traverse-lever, so that the longitudinal motion of the screwed shaft is imparted to the traverse-lever. By this traverse-lever, and its connections, I control the motions of my steam steering-engine, to be hereinafter described.

I have already described the screwed shaft D as a vertical shaft, driven in the bridge by the telegraph-shafting B C, and I have described a wheel and nut, D², as supporting this screwed shaft.

I will now explain how I work the telegraph-signals at the helm, to allow of steering by men at that point, when necessary.

On the screwed shaft, I fix a small spur-pinion, D¹, through which it receives motion, through the shafting B, from the telegraph forward, and on the nut D², I fix another similar pinion, from which I drive a small vertical shaft, G, there being thus one small shaft upon each side of the screwed shaft D, so that one of these shafts is driven by the telegraph-shafting, and the other by the wheel on the steering-wheel shaft, or, in other words, by the rudder-mechanism.

At the upper end of each of these shafts, C and G, I have a worm, C² and G², gearing each into a separate toothed arc or quadrant, F¹ and H¹, which are carried on the same centre, but work independently of one another. These worms or endless screws have their threads, the one, C², right hand, and the other, G², left hand, and the toothed arcs or quadrants have each an index-arm or pointer.

The index-arm F² of the arc H¹, which is moved by the rudder-mechanism, is in one piece with that arc, and indicates, on a graduated fixed dial, the actual position of the rudder. This index-arm, I call the rudder-indicator. The index-arm is jointed to both quadrants F¹ and H¹. The distance between the centres of these joints is short, as compared with the length of the index-arm, so that any difference in the motions of the two toothed quadrants F and H is shown as magnified at the point of this jointed index-arm F¹ H¹, and the steersmen at the steering-wheel are thereby directed to put the steering-wheel over to the side toward which this index-arm points. It travels over a graduated scale formed on the index-arm of the other toothed quadrant. This jointed index-arm H F, I call the telegraph-director.

It will be understood from this description that the

differential motions of the screwed shaft and nut-wheel, relatively to each other, produce similar differential movements of the two toothed quadrants relatively to each other, and that any difference between the movements of these two toothed quadrants is shown enlarged by the telegraph-director on the graduated scale formed on the rudder-indicator.

When the wheel at the bridge corresponds with the actual position of the rudder, the telegraph-director will point to the centre of the rudder-indicator arm, and that will then be the required position of the rudder.

It will be the duty of the steersman at the wheel to turn his wheel to one side or to the other, so as to maintain the telegraph-director in the centre of the rudder-indicator.

When the wheel at the bridge is moved in either direction, the telegraph-director will advance in the corresponding direction beyond the centre of the rudder-indicator, and will remain in advance until the actual position of the rudder corresponds with the required position, and then a telegraph-index at the bridge, the rudder-indicator at the stern, and the telegraph-director will all point to the same position for the rudder, and the telegraph-director will be central upon the rudder-indicator. This is the arrangement by which I convey a visible intimation to the helmsmen. In addition to this, I fix a bell and hammers on the upper end of the screwed shaft, and I fix a projecting pin on the nut-wheel, so placed as to give signals of warning, and, if required, so arranged as to strike repeatedly, for the signal of urgency.

In constructing this part of the apparatus, I prefer to have the hammers, one upon each side of the bell, and to bring the lifting-ends of the hammer-levers so close as just to leave clear space for the projecting pin on the nut-wheel to occupy a position between both levers, and clear of them both.

At the extremity of the lifting-end of each hammer-lever, I have a hinged tooth, to present an inclined face always to the pin, as they approach it, and to provide a sudden release to the hammer-lever, when the tooth has just passed the pin in either direction.

The hammer-levers are pressed by volute springs to force the hammers toward the bell, but they are kept just clear of the bell, each by a stop, bearing on the hammer-end of the lever.

When the hammer is lifted, and then suddenly released, the force of the spring carries the hammer on to strike the bell, the hammer-lever or shank bending a little at the stop; but after striking, the hammer is retained in a position clear of the bell, as is commonly done in engine-room telegraphs.

As I arrange that the screwed shaft has one free turn in either direction from its middle position, and as, when in its middle position, I place the projecting pin midway between the lifters of the bell-hammers, it follows, that in moving the telegraph-wheel to either side, the bell will be struck, giving a call to the steersman to attend to the signals.

When the bridge-wheel has been advanced one turn, the bell will strike again, giving the call again to the helmsman to attend to the signal, for port or starboard, as the case may be.

When one turn has been made in advance of the steering-wheel, and the signal is still unobeyed, the man at the bridge can, by shaking the wheel there through a small arc, cause the bell to strike repeatedly, for the signal of urgency. When the order has been fully obeyed, and the rudder arrives at the required position, the bell strikes one, and if carried past the required position, it will strike again, and the helmsman should bring his wheels to a position corresponding to midway between these two strokes of the bell, and then the telegraph-director will be central on the rudder-indicator.

It will be understood from this description that the sounding of the bell is only the signal for warning or attention. It is not an order to do anything, but a call to the order which is being signalled by the telegraph-director. This is the arrangement by which I convey an audible intimation from the man at the bridge to the helmsmen.

A telegraph-index at the bridge or place of governance is worked off the telegraph-shafting by a train of small wheels, to give the required motion to the pointer. The pointer may otherwise be moved by a worm or endless screw on the telegraph-shaft, with the requisite intermediate gearing. I prefer using spur-gearing for giving motion to this pointer, and the wheels I use are chosen from the change-wheels belonging to screw-cutting lathes. I thus get heavier wheels than are really needed, but they are less liable to damage than lighter wheels would be.

The position of the telegraph-index will correspond exactly with the motions of the telegraph-wheel, but it will be always in advance of the actual position of the rudder, while the rudder is being moved to orders, and behind the actual position of the rudder when it is being moved by the sea or against orders, and will exactly agree with the rudder in position, when orders given have been obeyed.

This is the arrangement by which I convey to the man at the bridge a knowledge of the position of the rudder.

At the bridge-shaft, which is a small horizontal shaft, I provide stops for the extreme positions of the rudder, namely, for hard-over port and hard-over starboard. I do this by cutting a strong screw on a part of this shaft. A traversing stop-nut is on this screw, and this nut is prevented from revolving with the shaft by a guide plate.

I fix stop-clutches on the shaft to gear with corresponding stop projections on the two sides of the traversing stop-nut, so that when the telegraph-index shows the extreme position for the rudder either way, one of these stop-clutches is in gear with the traversing stop-nut, and thereby the shaft is prevented from further movement in that direction.

This is the arrangement by which I limit the number of revolutions of the telegraph-shafting, to correspond with the range of the rudder.

At the bridge I connect the telegraph hand-wheel to the shaft, by means of a safety-clutch arrangement. The clutch is in two pieces, and the hand-wheel is fixed to, or formed on one of those pieces. It bears, at one side, upon a ring-collar, which is fixed on the end of the shaft. It is itself free upon the shaft.

A journal is formed on this clutch-piece, and a pedestal, under this journal, supports that end of the shaft. Upon the other side it is in contact with the other clutch-piece, and their driving projections there have inclined faces. This second clutch-piece is seated on feathers on the shaft, and can slide longitudinally on the feathers, and to transmit any force, these two clutch-pieces require to be held firmly together, or they would be thrown out of gear by the action of the inclined-driving faces. They are held in contact by a spiral spring on the shaft, bearing on the second clutch-piece, and compressed by a nut and screw, also upon the shaft.

The two clutch-pieces and the spiral spring are thus held firmly together between the ring-collar above referred to and this nut upon the shaft, and the force of the compression of the spring can be so regulated by the nut, according to the inclination of the faces of the clutch-pieces, and to the force which it will be safe to transmit through the shafting, that the clutches will part before any undue strain can be put upon the shafting, and the telegraph hand-wheel will then revolve without moving the shafting, and will thus intimate to the men in charge that the full signal has

been given and has not been executed, or that the rudder is hard over; but a man who is acquainted with the apparatus would never cause the clutches to slip, for he would know, by the increasing force required to move the wheel, that one of the stops was acting.

Very little force is required to move the shafting. I have revolved it with ease, applying only one finger to the telegraph hand-wheel at the bridge, driving, on the same motion, about four hundred feet of shafting and five pairs of mitre-wheels, carried by upward of fifty pedestals, besides driving the gear for the index-arms. This is the arrangement of safety-clutch by which I protect the telegraph-shafting from undue strains.

When the rudder is moved in opposition to the signal from the bridge, as when a sea strikes the rudder, the motion produced will first cause the rudder-indicator toothed quadrant to move in the same direction as the rudder, but, as the telegraph-shafting is stationary, the telegraph-director will move in the opposite direction, and when it has just reached the full signal for correcting the contrary motion of the rudder, the stop-clutches on the screwed shaft and on the nut-wheel will have come into gear, and if the contrary motion of the rudder is continued beyond this point, motion will be then imparted to the telegraph-shafting, and the telegraph-index on the bridge will indicate a position a little in the rear of the actual position of the rudder, as has been already explained.

The man at the telegraph hand-wheel should not resist the movement of that wheel when that is caused by the contrary motion of the rudder. His resistance will produce no effect beyond causing the safety-clutch to slip. He should wait until its motion has just stopped, and then move back the telegraph-index to the position he requires the rudder to occupy.

The description which I have given of my steering-telegraph and rudder-indicator applies, whether it is worked in connection with a steering-engine, or only with manual power at the steering-wheels. When in connection with the steering-engine, the contrary motion of the rudder would at once turn on the engine power to correct that motion, and it would seldom happen that the contrary motion would be continued so far as to move the telegraph-shafting, and therefore the telegraph hand-wheel, at the bridge, would, as a rule, only move when operated by the man in charge thereof. But all the while, even minute variations of the rudder would signal for their own corrections at the telegraph-dial aft, and by means of the traverse-lever, the differential motions produced would be communicated to the starting-lever of the steam-engine, which would respond to those signals, and restore the rudder to its required position, without the intervention of any attendant, either at the bridge or at the stern.

The steering-engine acts, under these circumstances, as a yielding but powerful brake, and restrains the rudder into its required position, acting, of its own accord, within the limits fixed by the traverse of the screwed shaft.

This is the arrangement by which contrary motions of the rudder signal their own correction, and apply the power of the engine to restrain the rudder.

The second part of my invention refers to a steam-steering engine, which I place at the stern, entirely under the control of the man at the bridge, and to be self-acting, to keep the rudder in any required position, or to restore it to that position, within certain limits, as above explained, against the action of the sea, and adapting the engine to be actuated by the telegraph-gear above described, and in several of its details providing for its efficient working as a special steering-engine.

To accomplish this, I construct an engine with two cylinders, (sometimes called a pair of engines, but in this specification I use the term "engine" to include the whole,) reversed by moving a special admission or stop-valve into one or other of its positions. I attach this admission-valve, by suitable connections, to a part of the telegraph-gear, the traverse-lever, $Q^1 Q^1 Q^2 Q^2$, which receives its motion from the screwed-shaft D, and I thereby open this stop-valve, according to the longitudinal motions of that screwed shaft, so that the position of this stop-valve, with reference to its whole travel, will always correspond with the position of the screwed shaft with reference to its longitudinal travel, and it will agree in its positions, also, with the positions and indications of the telegraph-director.

There is a spur-pinion, M³, on the engine-shaft M, gearing into a wheel, N¹, on the steering-wheel shaft N, of proper relative diameter.

I construct the engine-shaft M, and its pinion M³, so that the pinion M³ can be slid on feathers, on the shaft, to take it out of gear with the steering-wheel shaft, so that if the steering-wheel shaft N is also fitted with steering-wheels, as usual, the rudder can be worked either by steam-power or by hand, or by both, as is required, the telegraph and indicator remaining in use in either case.

If required, the spur-wheel M³ can be attached to the steering-wheel shaft by a friction-connection.

The steering-wheel shaft M³ may be either the shaft of a chain-barrel, or a screw, with side arms, or the screw or shaft for actuating hydraulic or other steering-apparatus.

The steering-engine, being in itself a complete engine, may be used for other purposes than steering.

The drawings accompanying this specification, from fig. 1 to fig. 14, inclusive, refer to the apparatus, constructed according to my invention, for the "Great Eastern."

In the accompanying drawings, figs. 1 to 14, inclusive, refer to the steering-apparatus of the Great Eastern, and to these all the preceding part of this specification applies. The figs. 15 to 18 inclusive, refer to modifications of the steering-telegraph and rudder-indicator. These drawings I will also now describe.

The drawings consist of five sheets.

Sheet No. 1 shows upon a small scale, 1=48, the general arrangement of the whole steering-gear.

Figure 1 is a side elevation of the steering-platform, steering-wheels, and steering-engine of the "Great Eastern."

Figure 2 is a side elevation of the apparatus at the bridge.

Figure 3 and Figure 4 are plans of fig. 1 and fig. 2.

On Sheet No. 2, scale 1=12, Figure 5 is a side elevation of the apparatus at the bridge or place of governance.

Figure 6 is a front view of the same.

Figure 7 is a plan of the same.

On Sheet No. 3, scale 1=12, Figure 8 is a side elevation of the steering-engine at the aft side, showing also the telegraph-director and rudder-indicator.

Figure 9, on the same sheet, is a plan of fig. 8.

On Sheet No. 4, scale 1=12, Figure 10 is an end elevation of the steering-engine from the port side.

Figure 11 is a sectional elevation of the same.

On Sheet No. 5, scale 1=12, Figure 12 is an end elevation of the steering-engine from the starboard side.

Figure 13 is a sectional plan of the cylinders and valves. The section is taken through the centre of the cylinders, and through the centre of the valves on the dotted lines shown from c to d in fig. 12.

Figure 14 is a cross-section through the cylinders in elevation.

The half of this figure on the left-hand side is taken

on the dotted line *a*, and the other half on the dotted line *b* in fig. 13.

On the same sheet, Figures 15, 16, 17, 18, refer to modifications of my invention to be hereinafter described.

The parts not above sufficiently described, are as follows:

*A*⁴, first half of safety-clutch. The bridge hand-wheel *A*¹ is fixed on this piece, and a journal is formed on it.

*A*⁵, the second half of safety-clutch. This piece is seated on feathers on the shaft, and it can slide longitudinally on the shaft on these feathers. *A*⁴ drives *A*⁵, and thereby drives the shaft. The driving-projections on *A*⁴ and on *A*⁵ have inclined driving-faces, so that *A*⁵ will slip out of gear from *A*⁴, unless they are held together.

*A*⁶, a spiral spring compressed to keep *A*⁴ in gear with *A*⁵, when not more than the safe amount of force is applied. When more force is used, the pressure acting on the inclined faces of the clutch, tends to part them with greater force than the compression of the spring, which tends to keep them in gear, and *A*⁵ slips out of gear from *A*⁴, and the hand-wheel rotates without communicating motion to the shaft. This special spring is in a telescopic case.

*A*⁷, nut for compressing the spiral spring *A*⁶. The thrust of the spring is borne by *A*².

*A*⁸, stop-clutches fixed on shaft *A*.

*A*⁹, traversing stop-nut. This piece is screwed as a nut, and traverses a screwed portion of the shaft. It has clutch-projections on each end to gear with *A*⁸ *A*⁸, when at either end of its travel, so as to limit the number of revolutions of the shaft.

*A*¹⁰, guide for *A*⁹, to prevent it from turning with the shaft.

*A*¹¹, mitre-wheel driving a similar wheel, *B*¹.

*B*³, cotter connecting the last length of *B* shafting to the machine at the stern. This cotter is removable, to allow the machine at the stern to be worked at the stern, independently of the bridge-gear.

C, the telegraph-shaft of the machine at the stern.

*C*¹, a cylindrical coupling.

*C*², a broad spur-pinion, gearing with *D*¹, an equal pinion.

*C*³, bearing for *C* in framing-piece *X*.

*C*⁴, ring-collar to bear the weight of shaft *C*.

*C*⁵, mitre-pinion to gear with *E*¹, a similar pinion.

*C*⁶, bracket fixed on framing. It forms a bearing for shaft *C*, and it carries a stop-wheel, *C*⁸.

*C*⁷, right-hand worm or endless screw, gearing with the quadrant *F*¹.

*C*⁸, stop-wheel. A portion of the circumference of this wheel is blank. The ends of the helix of the worm *C*⁷, strike on this blank part, and the number of teeth cut in the wheel is such as to allow of only the required number of revolutions. This stop is required only when the machine is worked by the aft hand-wheel *E*¹.

*D*², the nut-wheel, a mitre-wheel gearing with a similar wheel on the barrel-shaft. The centre of *D*² is a long boss screwed as a nut to work on the screwed shaft *D*. There is a neck-journal turned on this boss, and it is supported in bearing *D*⁸ in the framing-piece *X*. The centre of this wheel projects below the bearing *D*⁸, and there carries a pinion, *D*³, which forms the lower collar for the neck-journal. There are clutch-projections on the upper side of *D*² to gear into similar projections on *D*⁶. *D*² carries also a stud-pin on the upper side, to operate the hammers of a bell.

*D*³, a pinion keyed on *D*², and driving *G*¹, an equal pinion on the rudder-indicator shaft.

*D*⁴, a ground collar-piece fixed on the screwed shaft, and lifted or lowered with it. This piece carries the end of the traverse-lever, and thereby the differential motion of the screwed shaft is transmitted to the stop-valve of the steering-engine.

*D*⁵, a disk-clutch. The clutch-projections are on the bottom side, and gear with similar projections on *D*².

*D*⁶, bell with two hammers for the same, springs for the hammers, and a plate to which the hammers are attached. The bell itself is fixed on the upper end of the screwed shaft *D*, and with the stud-pin carried by *D*². These form a complete warning-bell, striking when the screwed shaft leaves its middle position either way, and when it returns to it; also when the signal for full speed over is given, and when it is withdrawn.

*D*⁸, bearing for *D*² in piece *X*.

E, shaft for aft hand-wheel. This shaft has two positions. In one position the pinions *E*⁴ and *C*⁵ are in gear, and in the other position they are out of gear.

*E*¹, aft hand-wheel. By this wheel the steering-engine can be operated at the stern.

*E*², a centre-plate with boss for supporting the shaft *E*.

*E*³, fig. 10, a pawl-piece, fitting either of the two grooves on the shaft *E*, and thereby retaining the shaft in the one or in the other of its two positions. This pawl-piece is hinged on a pin in ears at one side of the boss, and a similar pin-hole in ears at the other side admits a lock-pin or a padlock.

*E*⁴, a mitre-pinion on *E*, gearing and ungearing with *C*⁵.

*E*⁵, bracket supporting inner end of shaft *E*.

*F*¹, telegraph-quadrant. The worm *C*⁷ moves this quadrant.

*F*², magnifying telegraph-director. This is a pointer jointed on the indicator-quadrant, and also on the telegraph-quadrant. These joints are close to each other, so that any movement of one quadrant past the other quadrant is shown as enlarged at the extremity of the pointer.

G, indicator-shaft of the machine at the stern.

*G*¹, spur-pinion on lower end of *G*. This pinion is driven by *D*³, an equal pinion.

*G*², bearing for *G* on framing-piece *X*.

*G*³, bearing for upper end of shaft *G*.

*G*⁴, worm with left-hand screw on upper end of *G*, and gearing with indicator-quadrant *H*¹.

H, fig. 11, small shaft carrying *H*¹ fixed, and *F*¹ loose.

*H*¹, indicator-quadrant and pointer formed in one piece.

A segment-index scale is also formed on this pointer to measure the indications of the magnifying telegraph-director.

*H*², graduated index on *H*¹ for the magnifying telegraph-director.

*H*³, graduated index-segment for rudder-indicator, fixed on the framing or wooden casing.

J, figs. 13 and 14, the slide-valves of the engine; they are cylindrical, and therefore equilibrium. The passages are formed with a descent from the cylinder to the exhaust-pipe, to draw off any water of condensation.

K, the stop-valve for letting on the steam to the engine, does not form a working part of the engine, but is merely an admission-valve. When it is opened at one end, the engine rotates in one direction; when it is opened at the other end, the engine rotates in the opposite direction. The use of this valve is to reverse the engine, changing steam-passages into exhaust-passages, and exhaust-passages into steam-passages.

*K*¹, exhaust or steam or inlet-chamber of stop-valve.

*K*², outlet-chamber of stop-valve.

*K*³, cover for stop-valve, with stuffing-box and gland for the rod.

*K*⁴, stop-cock. By shutting this cock, the engine can be overhauled.

*K*⁵, rod of stop-valve.

*K*⁶, connecting-rod of stop-valve jointed to *Q*¹.

L, pistons of the engine.

*M*³, spur-pinion or crank-shaft. This pinion trans-

mits the power of the engine to the steering-barrel shaft by gearing with the spur-wheel N^1 , or to the winding-drums O^2 , by gearing with the two equal spur-wheels O^1 . This pinion slides on feathers on the shaft, and is held in any required position by the fork-arms P^1

N , the steering-barrel shaft. It is described here, and shown on the drawings, fig. 1, as a steering-barrel shaft with chains to the tiller, but it may be the continuation of the screw of a screw steering-apparatus, or of the steering-wheel shaft of any other form of steering-gear.

P , screwed shaft for drawing the pinion M^3 along the shaft, to gear it, or to ungear it with the rudder-gear, or with the winding-gear as required.

Q^4 , hand starting-lever, to be used when hoisting.

Q^5 , quadrant for guide for Q^4 .

It will be understood from the preceding description, that to operate the steering-engine, and to signal at the stern, I produce a longitudinal traverse motion, corresponding to the difference between the motion of the telegraph hand-wheel, and the motion of the steering-barrel shaft, by the intervention of a geared nut and screw between the steering-barrel shaft and the telegraph hand-wheel.

In figs. 15 to 18, inclusive, I show two modifications of my invention. In each of these I use a screw and a nut to produce differential traverse motion, and in each of these illustrations the nut gets its motion from the steering-barrel shaft, as in the first arrangement, but the details are here varied, to adapt them to other means of communication between the bridge and the stern.

It will be obvious that the steering-engine can be used without the telegraph, and the telegraph without the engine; that instead of connecting the steering-engine, directly to the steering-apparatus, the motion can be conveyed by intermediate gear, to allow of the engine being placed in any convenient position, for instance, in ships of war, below the water-line; and

that the engine-shaft can be formed on, or be an extension of a shaft of the steering-apparatus.

It will also be obvious, that instead of steam, any other power-fluid can be employed.

Having now described the nature of my said invention, and particularized the same, I would have it understood that I do not confine myself to the exact details and arrangements described herein, and shown on the drawings, as many modifications may be made without departing from the leading features.

What I consider to be new, and desire to claim as of my invention, is--

1. In combination with a steering-engine, a screw and nut, one of which receives a rotary motion from the engine, and the other from the attendant, arranged to produce a differential traverse motion, and thereby control the action of the steering-means, substantially as herein set forth.

2. A rotating shaft connecting the steering-mechanism with the engine, in combination with apparatus, arranged to produce a differential traverse motion to control the action, substantially as herein described, while the same is operated from the bridge or place of governance at will, as set forth.

3. The magnifying telegraph-director F^2 , constructed with two joints, substantially as herein set forth.

4. The quadrants $F^1 H^1$, operated by worms in the manner and for the purpose herein set forth.

5. Controlling the steering-engine and the steering-telegraph by one and the same motion-transmitter led from the place of governance, substantially as and for the purpose herein set forth.

In testimony whereof, I have hereunto set my name, in the presence of two subscribing witnesses,

JOHN MCFARLANE GRAY.

Witnesses:

JOHN T. KING,

ROBERT MOSS.
